E. F. M. SPEIDEL

CHAIN

Filed Nov. 9, 1925

Edwin F. M. Speidel, INVENTOR.

BY *Barlow & Barlow*
ATTORNEYS.

UNITED STATES PATENT OFFICE.

EDWIN F. M. SPEIDEL, OF EDGEWOOD, RHODE ISLAND.

CHAIN.

Application filed November 9, 1925. Serial No. 67,794.

This invention relates to improvements in the construction of chains or bracelets of the expandable type; and has for its object to provide a new and improved form of hinge or connection between the body or box-like links and sliding or connecting links, whereby the links may be readily connected to and disconnected from one another for the purpose of inserting or removing one or more of them to vary the operating length of the bracelet.

A further object of the invention is to construct a series of body links and a series of connecting links and connect these links of the different series with hinge elements shaped to be connected and disconnected from each other by being slid laterally one over the other, means being provided for preventing such relative movement, while the links are in operating position.

With these and other objects in view, the invention consists of certain novel features of construction, as will be more fully described, and particularly pointed out in the appended claims.

In the accompanying drawings:

Figure 1 is a side elevation showing my improved bracelet connected to opposite sides of a watch.

Figure 2 is a perspective view of the main portion of the body link with the back plate removed.

Figure 3 is a perspective view of the back plate of the body member showing the abutment for the spring and the coiled hinge elements on one end thereof.

Figure 4 is a perspective view of the connecting slide link showing the hook-shaped hinge elements which are to be connected to and disconnected from the hinge elements of the body link by being slid laterally thereover.

Figure 5 is a perspective view of the under side of one of the chain links, showing the body link with the hook-shaped hinge elements on one end thereof and the connecting slide link partially housed in the body link with the hook-shaped hinge elements on the outer end thereof.

Figure 6 is a sectional end view through the body link and the connecting link and showing the tension spring mounted therein.

Figure 7 is a side elevation showing the cooperating hinge elements of the body and connecting links separated.

Figure 8 is a top view of the hinge elements showing them staggered and in position to be connected.

Figures 9 and 10 are edge and top views, respectively, showing the hinge elements partly connected.

Figures 11 and 12 are edge and top view, respectively, showing the hinge elements in position to be slid laterally one over the other.

Figures 11 and 12 are edge and top views, respectively, illustrating the link members as having been slid laterally and swung up into operating position, in which position they are prevented from separation.

Figure 13 is a plan view sectioned on line 15-15 of Figure 1 showing a pair of body links connected by slide links partially extended.

Figure 14 is a sectional side elevation on line 16-16 of Figure 15.

It is found in the practical construction and use of bracelets of this character, of advantage to provide means whereby the links may be readily disconnected one from the other for the purpose of adding to or removing from, one or more links of the bracelet to change its working length; and to accomplish this in a simple and effective

way, I have formed a bracelet, the links of which have a hinge construction in which both the body link and the connecting link are provided with hinge elements shaped to be connected and disconnected from each other by being slid laterally one over the other, and a stop is provided for preventing such lateral sliding action while the links are in their operating position, that is, in order to separate the links they must be

first swung out of alignment at a sharp angle to each other in order to withdraw the stop, after which the link members to be moved laterally relatively to each other for ready disengagement; and the following is a detailed description of the present embodiment of my invention and showing one construction of hinge by which these advantageous results may be accomplished:

With reference to the drawings, 10 designates the body link which is formed more or less in box-shape, comprising a body portion 11 having a broad top plate 12 to receive suitable ornamentation, the edges of the side walls 13 of this body being provided with bendable flanges 14.

The back plate 15 is recessed longitudinally on its opposite edges and is adapted to be set upon the body member, the flange 14 thereof being rolled inwardly into these recesses 16 to firmly secure the back plate in position on the body thus forming a box-shaped link member.

One edge of this back plate 15, is turned inwardly as at 17 to provide an end abutment for the tension spring 18 and the opposite end of this back plate is provided with a pair of hinge members or fingers 19 which are offset laterally from the center thereof and which members have a space 20 between them approximately the width of one of the members.

As best illustrated in Figure 4, a connecting slide link 21 is mounted in the box link to slide endways therein, its rear wall 22 providing an abutment for the opposite end of the spring 18, the opposite end 23 of this slide link being provided with a pair of hook-shaped hinge members or fingers 24, preferably of a width substantially that of the hinge members 19 on the back plate of the body and the space between the hinge members 24 is of a width to receive the hinge members 19 on said back plate, whereby as best illustrated in Figures 10 and 12 these hinge elements may be caused to interlock or interengage with each other.

The members 24 are of a size to fit over the coils of the hinge members 19 so that when these hinge members are in axial alignment they may slide laterally relatively to each other into the position best illustrated in Figure 14, one pair being hooked over those of the other pair and after having been slid into that position they are swung back into longitudinal alignment in which position the edge 26 of the connecting link enters between the side walls 13 of the box link thus positively preventing lateral disengaging movement between these links.

In assembling the parts, it is only necessary to place the connecting slide link 21 in the box link, insert the spring 18, then apply the cover plate 15 to the box link and turn the edge flanges over to lock the same together.

It is now only necessary in connecting the different link units to insert the hinge elements 24 of the connecting link between those of the hinge elements 19 of the box link while set at a sharp angle to each other, and then slide these hinge elements one over the other and swing the links up into their normal working position where they are locked against disengagement, and any number of such links may be thus connected to form a chain of any desired length.

By my improved construction of chain the links of the different units may be quickly connected and disconnected from each other for the purpose of removing a dam-

aged link or inserting a fresh link for the purpose of adjusting the operating length of the bracelet.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A chain structure comprising a series of box links each having hinge fingers, a connecting link in each box link, hinge fingers on each connecting link interlocking with those on the next box link to hold said links hinged together.

2. A chain structure comprising a series of outer links, a series of inner links, extending hinge fingers on the links of each series, the hinge fingers of the links of one series interlocking with the hinge fingers of the next adjacent link of the other series to hold said links in hinged relation.

3. A chain structure comprising a series of box links, each having hinge fingers, a connecting link in each box link, hinge fingers on each connecting link interlocking with those on the next box link to hold said links hinged together, said interlocked links being relatively laterally movable when in certain relative positions to disengage said fingers, and stop means for preventing disengagement when said links are in working position.

4. A chain structure comprising a series of box links, each having hinge fingers, a connecting link in each box link, hinge fingers on each connecting link interlocking with those on the next box link to hold said links hinged together, said interlocked links being relatively laterally movable when in certain relative positions to disengage said fingers, and stop means for preventing disengagement when said links are in working position, said stop means being withdrawn upon swinging said interlocked links at right angles whereby the links may be disengaged by a lateral sliding movement.

5. A chain structure comprising a plurality of box links, a plurality of connecting links curled hinge fingers on the box links and on the connecting links interlocked in oppositely disposed relation when said links are in working position and foldable one within the other when said links are disposed at substantially right angles, whereby they may be disconnected by a lateral sliding movement.

6. In an extendible chain structure comprising a plurality of box links, a connecting link slidable in each box link, interconnecting hinge elements carried by each box link and connecting link, said elements being laterally slidable one over the other, stop

means carried by said slide link for engaging the next adjacent box link to prevent said sliding action, said means being disengageable from said box upon certain angular position of said adjacent links, whereby said lateral movement may be accomplished and a separation of said adjacent links accomplished.

7. An extendible chain structure comprising a series of box links, a connecting link slidable in each box link, interconnecting hinge elements carried by each box and connecting links, said elements being laterally slidable one over the other, and a portion of said connecting link engaging the side wall of the next adjacent box link to prevent lateral movement when said box links are in operating position but to permit withdrawal when positioned at an angle to each other.

8. An extendible chain structure comprising a series of body links, a series of connecting links slidable in the body link, each

link of each series having a plurality of co-operating spaced apart hinge elements arranged to be connected and disconnected by 25 sliding one over the other laterally, and means in the links for preventing such lateral movement when in operative position.

9. In an extendible chain structure, a plurality of box links each comprising a 30 trough-shaped member having shouldered side walls with bendable edge portions, a plate member resting on said shoulders and said edge portions bent thereover, an end wall carried by said plate and spaced from the bottom and sides of said trough, and a slide link having side walls slidable through the said spaces and having an abutment end wall, a spring acting between said end walls to draw said slide links within said box, and 35 means for attaching the connecting link to the next adjacent box link.

In testimony whereof I affix signature.

EDWIN F. M. SPEIDEL.
